UNITED STATES PATENT OFFICE

LEONARD L. RUGGLES, OF WHEATON, ILLINOIS, ASSIGNOR TO RESERVE HOLDING COMPANY, OF KANSAS CITY, MISSOURI, A CORPORATION OF DELAWARE

TELEPHONE SYSTEM

Application filed October 21, 1927. Serial No. 227,673.

The present invention relates to telephone systems in general, but is concerned more particularly with semi-automatic telephone systems, especially those wherein a number of small exchanges are interconnected by trunk lines with an operating center from which operators may control the automatic switching equipment in the various semi-automatic exchanges.

10 The broad general object of the invention is the production of suitable circuit arrangements whereby a common-battery semi-automatic telephone system of the character indicated above may be put into successful operation, all service features required in a commercial system being provided for. The invention has been applied to a system wherein the semi-automatic exchanges employ selectors and connectors.

20 In order to carry out the main object of the invention above stated, a number of dependent objects and features are involved as follows:

25 One object is to provide circuit arrangements such that two-way trunk lines may be used between the operating center and a semi-automatic exchange so as to increase the efficiency of the relatively small trunk group.

Another object of the invention is the provision of arrangements for seizing the semi-automatic exchange end of a two-way trunk line when a call is originated in a semi-automatic exchange and to automatically signal the operator, a talking circuit being effective 25 between the calling subscriber and the operator's switchboard when the operator responds.

It is a further object of the invention to destroy the talking circuit when the operator is operating the automatic switches so as to prevent severe clicks from being heard by the calling subscriber, this being done by short circuiting the calling line while the switches are being operated.

40 A feature of the invention is found in the arrangements whereby the calling line is switched through from a selector to a connector when the connector is seized, the connector being operated over a separate impulsing conductor independent of the talking cir-

cuit. In connection with this arrangement, a connector can be operated either over the above mentioned separate impulsing conductor or over the talking conductors, depending upon whether the call is a purely local 55 call or an incoming call from the operating center.

Another object of the invention is to provide for the handling of party-line service by providing connectors equipped with party selectors and by providing ring-back switches for use in reverting calls for operating the calling and called sub-station ringers alternately. In carrying out this object, arrangements have been provided for preventing a 60 premature operation of the ring-back switch by maintaining the calling line short circuited at the first selector until the operator has withdrawn from the connection.

65 A feature of this arrangement is found in the ring-back switch wherein suitable circuit arrangements are provided for preventing the ringing operation from being started when the operator withdraws from the connection, such ringing operation being held up until 70 the calling subscriber replaces his receiver.

75 Another object of the invention is to make suitable provision for placing an out-of-order tone on a calling line when an attempt is made to complete a connection to a line that is out of order, the out of order condition being transmitted to a connector switch through a separate wiper from a separate conductor associated with the called line terminals. As 80 the most frequent out-of-order condition of 85 a line is for the live side of the line to be grounded or for the two conductors of a line to be inadvertently connected together, in which case the lineswitch individual to the line seizes a first selector and causes the operator to be signalled, a certain level of the selector being reserved for receiving out-of-order calls and for placing an out-of-order potential on the out-of-order conductor individual to a defective line.

90 In developing the system described herein, it has been assumed that local calls within a semi-automatic exchange are completed under the control of a so-called local operator in the operating center, and that incoming calls 95

are completed through a toll board presided over by one of the toll operators. It has been assumed further that the toll operators use common-battery cord circuits wherein standard loop supervision is employed, while the cord circuits used by the local operators are of the so-called dark-shelf type, wherein the calling supervisory lamp is extinguished upon the operation of the ringing key. Now, when a local operator makes a call from a subscriber local to the operating center to a subscriber in a semi-automatic exchange, it is unnecessary for such operator to operate her ringing key. It is accordingly an object of the invention to provide circuit arrangements associated with the trunk line extending to the semi-automatic exchange to extinguish the calling supervisory lamp automatically without obliging the operator to operate her ringing key, while the calling supervisory lamp in a toll cord circuit is not extinguished until the called subscriber in the automatic exchange has responded.

Referring now to the accompanying drawings comprising Figs. 1-5, they show by means of the usual circuit diagrams a sufficient amount of apparatus in a semi-automatic telephone system embodying the features of the invention to enable the invention to be understood. In order for the drawings to be understood best, Fig. 2 should be placed to the right of Fig. 1 with the interconnecting lines in alignment; Fig. 5 should be placed beneath Fig. 2; Fig. 4 should be placed beneath Fig. 1; and Fig. 3 should be placed to the left of Fig. 4.

When the drawings are laid out in the above manner, Figs. 1 and 2 show the switching equipment comprising a lineswitch, a selector, and a connector necessary to complete a connection from the line of substation A, Fig. 1, to the line of the substation B, Fig. 2, both lines terminating in the same semi-automatic exchange.

Fig. 5, shows a ring-back switch accessible to the selector shown in Fig. 1 and arranged to signal alternately the calling and called stations on a party line.

Fig. 3 shows the operating-center end of a two-way trunk line connecting the operating center with the semi-automatic exchange shown in Figs. 1, 2, 4, and 5. The equipment shown in Fig. 3 includes the trunk circuit TC1 with the associated jacks at the toll board and at the local board, together with the dial cord DC at the local board for associating the dial type calling device CD with any of the trunk lines through dial jacks such as the dial jack DJ2, associated with the trunk circuit TC.

Fig. 4 shows the semi-automatic exchange end of the trunk line comprising conductors 314 and 315, which trunk line terminates in the incoming selector. This drawing shows also the secondary switch SS, individual to

the local selector shown in Fig. 1 and having access to the inter-exchange trunk lines, such as the one comprising conductors 314 and 315. This is the switch which operates when the local selector shown in Fig. 1 is seized and seizes a trunk line to signal the operator in the operating center.

The invention having been described generally, a detailed description of the operations of the apparatus shown will now be given. For this purpose it will be assumed that the subscriber at substation A, Fig. 1, desires to converse with the subscriber at substation B, Fig. 2.

Local call in the semi-automatic exchange

When the receiver is removed at substation A, line relay 108 of the lineswitch LS operates over the calling line and starts the lineswitch LS into operation by grounding the private normal conductor 104 and by connecting up test wiper 111 to the junction of switching relay 108 and stepping magnet 109. If the trunk line on which the wipers 110-113 are standing is idle, no advance of the wipers takes place, and switching relay 107 operates in series with magnet 109. If, however, the trunk line is busy, a ground potential is encountered by test wiper 111; switching relay 107 is short circuited; and the self-interrupting magnet 109 operates in a buzzer-like manner to advance the wipers of the switch. This operation continues until an idle trunk line is reached, for example, the trunk line comprising conductors 114-117 and extending to the local selector shown in the drawings. When this idle trunk line is reached, the action of magnet 109 ceases and switching relay 107 operates in series with said magnet. Magnet 109 does not operate in series with relay 107 owing to the relatively high resistance of the latter.

When relay 107 operates it connects up wiper 112 at its inner lower armature; opens a point in the test circuit and prepares the holding circuit for the lineswitch at its inner upper armature; and at its upper and lower armatures it disconnects the conductors of the calling line from line relay 108 and ground and extends them by way of wipers 110 and 113 and trunk conductors 114 and 117 to the line relay 121 of the local selector through contacts of switching relay 126. Line relay 121 now operates over the calling line and places a ground at its inner upper armature on release trunk conductor 115, thereby closing the usual holding circuit for the lineswitch LS before the slow-acting line relay 108 has fallen back.

In addition to placing the ground potential on the release trunk conductor of the selector, line relay 121 closes at its inner lower armature a circuit over conductor 135 for switching relay 401 and stepping magnet 405 of the secondary switch SS. At its middle

lower armature, line relay 121 connects test wiper 403 of the switch SS to the junction of the switching relay 401 and stepping magnet 405, thereby setting the switch into operation. The switch SS operates in the manner described in connection with the lineswitch LS, selecting an idle trunk line; for example, the trunk line comprising conductors 314 and 315, extending from the semi-automatic exchange to the manual exchange shown in Fig. 3. When this idle trunk line is reached, switching relay 401 operates and connects up the associated wipers 402—404. When the wiper 403 is grounded by relay 401, a circuit is closed over the test conductor of the seized trunk line and through normally closed contacts of release relay 408 for cut-off relay 406. Relay 406 operates and disconnects the conductors 304 and 305 from line relay 407 of the selector and connects them instead to the conductors extending to the bank of the switch SS, thereby connecting impulse relay 122 of the local selector, Fig. 1, to the conductors 314 and 315. It will be noted that relay 407 is connected to the conductors 314 and 315, normally, so that there is a ground potential on conductor 315 and a negative-battery potential on conductor 314. It will be noted, further, that relay 122 of the local selector is now connected to conductors 314 and 315 in such a way that the opposite potentials are placed on the said conductors, conductor 314 now being supplied with battery potential through the upper winding of relay 122, and conductor 314 being supplied with ground potential through the lower winding of the said relay.

In the manual exchange, line relay 301 of the trunk circuit TC1, which is normally connected between ground and conductor 315 and which normally remains non-operated due to the ground potential on conductor 315, now operates due to the battery potential placed on conductor 315 through the upper winding of relay 122, Fig. 1. Although 301 operates, relay 122 does not operate due to the relatively high resistance of relay 301. When relay 301 operates it closes a circuit for the associated call lamp at the local board.

When the operator notes the lighted condition of the call lamp, she inserts the answering plug of an idle cord circuit into the jack J2, whereupon the discriminating relay 303 of the trunk circuit TC1 is operated through the upper spring contacts of the jack J2, but its operation is of no particular utility in connection with an incoming call. As a further result of the plugging-in operation, sleeve relay 302 places ground on conductor 321 at its inner armature, thereby closing a lighting circuit for the busy lamp and preparing certain locking circuits in trunk circuit. Relay 302 also disconnects the incom-

ing trunk conductor 315 from line relay 301 and completes a bridge across conductors 315 and 314 through the polarized relay 306 and the associated high resistance 311. The polarized relay 306 does not operate in this bridge owing to the fact that the current flow is in the reverse direction at this time, negative potential being supplied to the positive conductor in the semi-automatic exchange and a positive potential being supplied to the negative conductor. The impulsive relay 122, Fig. 1, is not operated at this time owing to the inclusion of the high resistance 311 in the bridge across the conductors 314 and 315. It will be noted that a bridge exists across the tip and ring conductors of the jack J2 through the upper contacts of relay 304, lower winding of relay 308, and the inner lower contacts of relay 310. Relay 308 operates in this bridge from the regular battery-feed circuit of the cord and closes a locking circuit for its upper winding at its upper armature, which locking circuit includes the inner upper contacts of the non-operated relay 304 and the inner upper contacts of the operated relays 303 and 302. Relay 308 also disconnects the lower terminal of relay 307, but this does not produce any particular effect at this time. Since the above mentioned bridge is across the tip and ring conductors of the jack J2, the current flow through the usual supervisory relay of the cord suffices to operate this relay to extinguish the supervisory lamp so as to give the operator answered supervision.

The operator now converses with the calling subscriber at substation A, Fig. 1, the voice current passing through the condensers at the local selector shown in Fig. 1. Upon learning that the subscriber at substation A desires to converse with the subscriber at substation B, the operator proceeds to insert the plug P of the dial cord DC into the dial jack DJ2 of the trunk line in use and to dial the digits in the desired number.

When the plug P is inserted into the dial jack DJ2, the dial circuit including the impulse springs of the calling device CD and contacts of the release key RK in series is placed across the tip and ring conductors leading to the dial jack, and the off-normal conductor of the calling device is connected through the sleeve of the plug P to the sleeve conductor extending to the off-normal relay 313, but there is no immediate current flow through the dial cord. At the upper spring contacts of the jack, a circuit is closed for relays 304, 305, 309, and 310 in multiple, but the operation of relays 304, 305, and 309 is of no particular utility at this time. Relay 310 connects the tip and ring conductors of the dial jack to the trunk conductors 314 and 315, at the same time disconnecting these trunk conductors from the talking conductors associated with the jack J2. Relay 310 also

opens the tip and ring supervisory bridge, whereupon unanswered supervision is indicated in the operators cord circuit.

Impulse relay 122 of the local selector, Fig. 1, now energizes over conductors 314 and 315 and through the contacts of relay 313. Upon operating, relay 122 of the local selector closes a circuit for release relay 123, whereupon relay 123 operates and prepares a circuit for the vertical magnet 131 at its inner lower armature, at the same time opening a point in the release-magnet circuit at its lower armature and closing a short circuit across the talking circuit at its upper armature so as to prevent the calling subscriber from hearing the clicks as the digits are dialled.

After having inserted the plug P, Fig. 3, into the dial jack DJ2, the operator dials the first digit 2 in the desired number by means of the calling device CD. When the calling device is moved from its normal position, the off-normal contacts place ground on the sleeve of the plug P, closing a circuit through the sleeve of the jack for off-normal relay 313. Relay 313 removes the short circuit from across the dialling conductors, leaving the dialling circuit under the control of the impulse springs of the calling device. As the calling device returns to its normal position, the circuit is interrupted twice at the impulse springs.

When the calling device reaches its normal position, relay 313 falls back and replaces the shunt across the impulse leads. Due to this arrangement whereby the impulse circuit of the calling device is shunted except when the calling device is off-normal, preliminary impulses are prevented when the plug is inserted into the jack and a momentary opening of the impulse circuit is prevented when the plug is withdrawn from the jack.

Following the dialling of the first digit 3, the operator dials the two digits necessary to bring the wipers of the connector into engagement with the terminals of the line of substation B, followed by the party selecting digit 6 necessary to operate party selector to signal the substation B as will be hereinafter explained.

Having dialled the complete number, the operator removes the plug from the jack J2, as well as removing the plug P from the jack OJ2, whereupon the various relays of the trunk circuit TC1 fall back and relay 122 of the local selector, Fig. 1, falls back. The call lamp associated with the trunk circuit TC1 is not again operated because the switch SS, Fig. 4, immediately releases and frees the trunk line in a manner to be pointed out hereinafter.

The setting of the switches in response to the digits dialled by the operator will now be explained. When the first digit 2 is dialled, impulse relay 122 of the local selector,

Fig. 1, falls back twice momentarily, closing, each time it falls back, a circuit through the inner lower armature of release relay 123, inner lower armature, normal, of switching relay 126, and series relay 124 for vertical magnet 131. By the operation of the vertical magnet the wipers 127-130 are raised step by step until they come to rest opposite the second level of bank contacts. Relay 124 operates upon the delivery of the first impulse, and, being slow-acting, remains operated throughout the digit. Relay 124 prepares a circuit from the grounded release trunk conductor 115, which is completed upon the closure of the off-normal contacts through the interrupter contacts of rotary magnet 132 for stepping relay 125. Relay 125 operates and closes a self-locking circuit at its upper contacts, through the middle lower contacts of the switching relay 126, and at its lower contacts it prepares the circuit of the rotary magnet.

At the end of the vertical movement, the series relay 124 falls back and opens the initial circuit of the stepping relay, leaving the stepping relay energized over its locking circuit, at the same time completing a circuit from the grounded release trunk conductor 115 for the rotary magnet 132. When the rotary magnet operates it advances the wipers 127-130 one step in a horizontal direction, whereupon they encounter the first set of bank contacts in the second level. Near the end of its stroke, magnet 132 disconnects stepping relay 125, whereupon relay 125 falls back and closes its interrupter contacts again. The further operation of the selector depends upon whether or not the first trunk line is idle. If this trunk line is idle, switching relay 126 now operates, seizing the trunk. Assuming that the trunk line is busy, a ground potential is encountered on the test contact thereof by test wiper 128, and relay 125 reoperates, shunting relay 126 and causing the rotary magnet to reoperate and advance the wipers another step.

This alternate operation of the stepping relay and the rotary magnet continues until an idle trunk is reached, which trunk it will be assumed is the one comprising conductors 145-148. When this trunk is reached, relay 125 does not operate again owing to the fact that no ground potential is encountered by wiper 128, and switching relay 126 operates from the grounded release trunk conductor 115 in series with relay 125, through the associated off-normal and the interrupter contacts. Relay 125 does not operate in series with relay 126 owing to the relatively high resistance of the latter. Upon operating, relay 126 opens a further point in the circuit of release magnet 133 at its middle lower armature, disconnects impulse conductor 139 from the vertical magnet 131 and sends it to impulse wiper 129 at its inner lower armature.

ture; opens a point in the test circuit and connects test wiper 128 to the grounded release trunk conductor 115 at its inner upper armature; and at its upper and lower armatures it disconnects the incoming conductors 114 and 117 from line relay 121 and extends them by way of wipers 127 and 130 to conductors 145 and 148 of the connector shown in Fig. 2. Line relay 121 of the local selector, having been disconnected from the talking conductors 114 and 117, would ordinarily fall back and cause the connection to be released if it were not for the fact that its circuit is held closed at the upper contacts of release relay 123.

In the connector, Fig. 2, line relay 203 now energizes over the calling line and over conductors 145 and 148 and through contacts of relays 201 and 202 and closes a circuit for release relay 204. Relay 204 operates and prepares the switch for operation.

When the operator dials the second digit in the number, impulse relay 122 of the local selector again responds, but the impulses are this time transmitted over impulse conductor 139 and through impulse wiper 129 by way of the inner lower armature of the operated switching relay 126. The impulses are transmitted further over impulse conductor 147 to the connector and then to vertical magnet 215. The circuit of the vertical magnet includes, at the time of its first closure, the lower armature, operated, of release relay 204, normally-closed off-normal contacts, and series relay 205. By the operation of the vertical magnet, the wipers 211-214 are raised opposite the desired level of bank contacts. Slow-acting relay 205 responds to the current flow through the vertical magnet and remains operated throughout the digit. This relay maintains its own circuit and that of the vertical magnet intact after the off-normal contacts have shifted.

At the end of the vertical movement, relay 205 falls back and transfers the impulsing conductor from the vertical magnet to the rotary magnet 216.

When the next digit is dialled, the impulses of current pass through the restored armature of relay 205 to the rotary magnet, the circuit at the time of its first closure including contacts of busy relay 207 and the inner-lower armature of switching relay 209. Relay 208 operates in multiple with the rotary magnet and transfers test wiper 212 from the test winding of switching relay 209 to the winding of busy relay 207 at its upper armature, and at its inner lower armature it shunts the corresponding contacts of busy relays 207 so as to maintain the operating circuit intact in case relay 207 operates during the rotary movement of the switch.

The operation taking place at the end of the rotary movement of the connector depends upon whether the line of substation B

is busy or idle. Assuming first that the line is busy, busy relay 207 is operated through test wiper 212 when the wipers come to rest in engagement with the bank contacts of the called line. Then, when slow-acting relay 208 falls back it completes a locking circuit for the busy relay from the grounded release trunk conductor 146 through the inner upper armature of the busy relay and through contacts of relays 208 and 209. In this case, no further impulses can be delivered over the impulse conductor owing to the fact that this conductor is open at the contacts of relays 207 and 208. A busy tone is now placed on the lower talking conductor and is transmitted to the calling subscriber as soon as the operator has finished dialing. The automatic switches are released as soon as the calling subscriber replaces his receiver.

Assuming now that the line is idle, the busy relay 207 is not operated when the wipers land on the contacts of the called line, and switching relay 209 operates from ground on release trunk conductor 146 to battery encountered on the private normal conductor by test wiper 212, its circuit including the upper armature, normal, of relay 208, the lower winding of relay 209, and the inner upper armature, normal, of busy relay 207.

The cut-off relay of the lineswitch on the called line (corresponding to relay 107 of the lineswitch LS) operates half way only, due to the interlocking arrangement between the cut-off relay and the line relay, disconnecting the line relay, but not connecting up the wipers of the switch.

In the connector, relay 209, upon operating, places ground directly, at its upper armature, upon test wiper 212 independent of its own lower winding; opens a point in the circuit of busy relay 207 at its middle upper armature so as to prevent the operation of the busy relay during the setting of the party selector; closes a locking circuit for its upper winding at its inner upper armature; opens a point in the busy-tone circuit and closes a point in the ring-back-tone circuit at its lower armature; and at its inner lower armature it disconnects the impulsing conductor from rotary magnet 216 and extends it to the operating magnet of the party selector.

When the party-selecting digit is dialled, the digit 6 in this case, the impulses of current are delivered to the operating magnet of the party selector with the result that the wipers 221 and 222 are advanced step by step until they come to rest on the sixth set of bank contacts. The off-normal contacts of the party selector close a point in a new circuit for busy relay 207, but this circuit is maintained open at the contacts of relay 208 until this relay falls back at the end of the party-selecting digit. When relay 207 reoperates it places a ring back tone on the lower talking

conductor through its own lower armature and through the lower armature, operated, of switching relay 209. Relay 207 at its inner lower armature opens the impulse conductor so as to prevent further operation of the operating magnet of the party selector in case the impulse conductor is grounded again; it prepares a circuit for the release magnet of the party selector at its middle upper armature; and at its upper and lower armatures it disconnects the talking wipers 211 and 214 from the auxiliary backbridge relay 202 and connects them instead to the wipers 221 and 222 of the party selector. At this time, wiper 221 is standing on its sixth associated bank contact which is connected through the equipment shown in Fig. 5 to battery directly, or to battery through the 66-cycle generator, depending upon the position of the relay controlled by the interrupter 12. Accordingly, ringing current from the 66-cycle generator is transmitted intermittently over wiper 222 of the party selector and through wiper 214 of the connector to the lower conductor of the called line, operating the ringer at substation B.

When the subscriber at substation B responds by removing his receiver, he opens his ringer circuit and closes a direct-current bridge across the talking conductors, whereupon the ring-cut-off relay 206, which is connected between the grounded conductor 218 and the bank contact on which wiper 221 of the party selector is now standing, operates through wiper 211 of the connector and over the upper conductor of the called line. Upon operating, relay 206 closes a locking circuit for its upper winding at its inner upper armature; and at its upper and lower armatures it disconnects the wipers 211 and 214 from the wipers of the party selector and connects them instead to the windings of back-bridge relay 201, thereby completing the talking circuit. The ring-back-tone circuit is opened at the normally-closed contacts controlled by the lower armature of relay 206.

Back-bridge relay 201 now operates and reverses the connection between the incoming conductors 145 and 148 and the windings of line relay 203, but this reversal is of no particular utility in this connection.

Considering now the effect produced in the semi-automatic exchange when the operator removes the plugs from the jacks DJ2 and J2, Fig. 3, when this occurs, impulse relay 122, Fig. 1, falls back and delivers another impulse through wiper 129 and over conductor 147 to the connector, but no harm results because the impulse circuit is open at the inner lower contacts of relay 207 and 208.

After an interval, release relay 123 of the local selector falls back and opens the impulse conductor at its inner lower armature; and at its upper armature it opens the circuit of line relay 121, whereupon line relay

121 falls back and removes ground at its inner upper armature from the trunk conductor 115, leaving conductor 115 grounded from the grounded release trunk conductor 146 of the connector, Fig. 2, through wiper 128 and the bank contact on which it is standing. At its middle lower armature, line relay 121 opens a point in the test circuit of the secondary switch SS, and at its inner lower armature it opens the circuit of switching relay 401, whereupon relay 401 falls back, freeing the trunk line comprising conductor 314 and 315. When the trunk line is freed and the local release trunk conductor 450 thereof is ungrounded at the contacts of relay 401, slow-acting relay 406 of the incoming selector falls back and reconnects the conductors 314 and 315 to the windings of line relay 407. Since the polarity of the connection made through impulse relay 122 to the conductors 314 and 315 is opposite to the polarity of the connection made through line relay 407, relay 406 is made slow-acting so as to delay slightly the connecting up of line relay 407 so as to give time for the charge placed on the trunk line by the impulse relay to partially dissipate itself before the line relay 407 is connected to the trunk line.

It may be pointed out that it is the above clearing out operation in the semi-automatic exchange that prevents a reoperation of the call lamp, Fig. 3, when the operator pulls down her plug after having dialled up the number desired in the semi-automatic exchange.

Regarding the established connection, the two subscribers are able to converse with each other as soon as the ring cut-off relay 206 of the connector operates as above described. When the conversation is over, the two subscribers replace their receivers, and the back-bridge relay 201, Fig. 2, falls back and reverses the current flow in the incoming conductors to normal, when the receiver is replaced at substation B.

When the receiver is replaced at substation A, line relay 203 of the connector falls back and opens the circuit of the associated release relay 204. Relay 204 falls back after a slight interval and removes ground from release trunk conductor 146 at its upper armature, whereupon switching relay 126 of the local selector and switching relay 107 of the line switch LS both fall back. When relay 126 of the local selector falls back, it completes at its middle-lower armature a circuit through contacts of relays 121 and 123 for release magnet 133 through the associated off-normal contacts. As a result, the selector releases in the usual manner, the release magnet circuit being opened again when the normal position is attained.

As a further result of the deenergization of release relay 204 of the connector, ground

is removed from conductor 218 at the inner-upper armature of the relay, whereupon the locked up relays 206 and 209 fall back. As a further result of the deenergization of relay 204 a circuit is closed at the upper-armature of the relay through contacts of relay 207 for the release magnet of the party selector. The release magnet of the party selector operates and restores the party selector to normal, whereupon the off-normal contacts of the party selector open the circuit of relay 207. Relay 207 falls back and opens the circuit of the release magnet at its middle upper armature. The release magnet 217 of the connector operates through the associated off-normal contacts and through the lower armatures of relays 203 and 204, restoring the connector to normal in the usual manner.

The entire connection is now released and the apparatus involved therein may be used in setting up a subsequent connection.

It will now be assumed that the subscriber at substation A desires to converse with another subscriber on the same line, for example the subscriber who has the 50-cycle ringer connected between the upper line conductor and ground.

Reverting call

When the subscriber at substation A removes his receiver, the lineswitch operates in the hereinbefore described manner and seizes a local selector, the one shown in Fig. 1, for example. When the local selector is seized, line relay 121 operates over the calling line in the hereinbefore described manner and causes the secondary switch SS to select an idle trunk, for example the trunk comprising conductors 314 and 315. When this trunk is seized, the operator is signalled as before described and she responds and converses with the calling subscriber. Upon learning that the call is for another station on the same line as the calling line, the operator associates her calling device with the trunk line over which the call was received after which she dials the ring-back digit 1, followed by the two digits necessary to set the ring-back switch such as the one shown in Fig. 5, into the correct position to signal the calling and called stations alternately. The subscribers are instructed to leave their receivers off the hook until they hear a hang-up tone, which is placed on the calling line at the proper time as will be hereinafter explained. Then, after the calling subscriber hangs up his receiver in response to this hang-up tone the ringers of the two substations operate alternately until the called subscriber responds.

When the operator has inserted the plug P into the dial jack DJ2, Fig. 3, and has dialled the digit 1, the local selector, Fig. 1, raises its wipers 127-130 opposite the first

level of bank contacts in the usual manner and selects an idle trunk, for example the one comprising conductors 141-144 and extending to the ring-back switch shown in Fig. 5. When this trunk line is reached, switching relay 126 operates and extends the incoming conductors 114 and 117 to wipers 127 and 130 to the conductors 141 and 144. The line relay 121 of the local selector is maintained energized through the upper contacts of release relay 123 after switch relay 126 operates. It will be noted that there is a local bridge across conductors 114 and 117 in this case through the upper contacts of line relay 121 and through the first-level shaft springs. This local circuit is established in order that the line relay 503, Fig. 5, of the ring-back switch will remain operated until the connections to the operating center has been released upon the disconnect operation of the operator in case the calling subscriber replaces his receiver prematurely.

When the ring-back switch is seized, its line relay 503 energizes over conductors 141 and 144 and through the bridge across the conductors 114 and 117 of the local selector, Fig. 1, and closes at its inner lower armature a circuit for release relay 504. Relay 504 operates and prepares the impulse circuit at its lower armature; prepares a locking circuit for relays 505 and 507 at its inner upper armature; and at its upper armature it places ground on the release trunk conductor 142 so as to maintain the local selector and the calling lineswitch operated. When release trunk conductor 142 is first grounded, which occurs when the ring-back switch is seized, a circuit is closed through the associated off-normal contacts for the combination change-over and reversing relay 502. Relay 502 operates and prepares at its inner upper armature a locking circuit for itself, and at its inner lower armature it disconnects the rotary magnet and connects up the vertical magnet.

When the operator dials the next digit, the impulses of current are delivered through the impulse wiper 129 of the local selector and over conductor 143 to the vertical magnet 516, through the lower armature, operated, of relay 504, middle lower armature, normal, of relay 505, and the inner lower armature, operated, of relay 502. By the operation of the vertical magnet, the wipers 510-513 are raised step by step opposite the desired level of contacts, which level it will be assumed is the one shown in the drawings. Relay 506 is operated in multiple with the vertical magnet and it remains operated throughout the digit. Upon operating, relay 506 completes at its upper armature the locking circuit for relay 502 through the inner upper contacts of the said relay. This locking circuit maintains relay 502 operated after its initial circuit is opened at the associated off-normal

contacts upon the initial upward movement of the switch.

When the impulses have ceased, relay 506 falls back and opens the locking circuit of relay 502, and relay 502 falls back and disconnects the vertical magnet 518, connecting up the rotary magnet 519.

When the next and last digit is dialled, rotary magnet 519 responds and rotates the wipers 510-513 into engagement with the desired set of contacts, in this case the contacts 514-517. Relay 506 is operated throughout the digit, as before, and it maintains the wipers disconnected.

At the end of the rotary movement, relay 506 falls back and connects up wipers 510, 511, and 513, whereupon the wiper-switching relay 509 is placed under the control of the interrupter I1 through bank contact 515 and wiper 511, and a circuit is closed from battery over one of the ringing leads and through bank contact 516 or 517 and wiper 512 or 513 for the lower winding of relay 505. The path over which this circuit becomes effective depends upon whether or not the relay 509 is operated immediately by the interrupter I1. When relay 505 operates, it closes a locking circuit for itself at its upper armature through contacts of relay 504; opens its initial circuit at its inner lower armature; and at its lower armature disconnects the impulse conductor from the magnet circuit and prepares a circuit for operating the hang-up relay 501 as will be described subsequently.

The circuit of relay 501, when completed, includes the lower contacts of line relay 503. Therefore, this circuit cannot be completed until line relay 503 is permitted to fall back.

When the operator initiates the operator-disconnect operation by removing the plugs from the jacks J2 and DJ2, Fig. 3, impulse relay 122, Fig. 1, falls back and opens the circuit of release relay 123, whereupon relay 123 falls back and opens the circuit of line relay 121. Line relay 121 falls back and causes the secondary switch SS, Fig. 4, to free the trunk line extending to the manual office. Line relay 121 opens at its upper armature the holding circuit across conductors 114 and 117, thereby placing the line relay 503 of the ring-back switch, Fig. 5, under the direct control of the calling substation. During the interval required for release relay 123 to fall back after line relay 122 has fallen back, a ground potential is placed on impulse conductor 143 through impulse wiper 149, but this impulse of current does not operate the hang-up relay 501, due to the fact that line relay 502 of the ring-back switch is still operated due to the bridge across conductors 114 and 117 at the local selector, which bridge holds the line relay of the ring-back switch operated regardless of whether the calling subscriber has hung up or not.

Referring now to the ring back switch, it

will be noted that there is a circuit from the hang-up-tone conductor through the associated small condenser and off-normal contacts to the lower talking conductor 144. This circuit is closed as soon as the ring-back switch is moved from its normal position, but the tone is not heard by the calling subscriber until the short circuit is removed from conductors 114 and 117 at the upper contacts of relay 121 when the operator disconnects from the connection. Upon hearing the tone produced at this time, the calling subscriber replaces his receiver, whereupon line relay 503 falls back and at its inner lower armature closes a circuit through the lower armature, operated, of release relay 504, middle-lower armature, operated, of relay 505, lower contacts of line relay 503, and the lower armature, normal, of ring-cut-off relay 507 for hang-up relay 501. Relay 501 operates and closes at its inner lower armature a circuit for relay 504 so as to maintain the release relay operated for the time being. At its upper and lower armatures, relay 501 disconnects the incoming conductors 141 and 144 from the windings of the line relay and connects them instead to the ringing circuit and to ground through the contacts of the reversing relay 502. The reversing relay 502 and the generator-switching relay 509 are controlled by the interrupter I1, through wipers 510 and 511. When the ringing current is placed on the ringing conductors with relays 509 and 502 restored, current from the 50-cycle source passes out to the ringing circuit through bank contact 517, wiper 513, armature of relay 509, contacts of relay 507, winding of relay 508, and the upper contacts of relays 502 and 501 to the upper conductor 141. This ringing current passes back over the connection to the upper conductor of the calling line and operates the 50-cycle ringer connected between the upper line conductor and ground. Now, when the interrupter I1 moves into its alternate position and operates relay 502 through bank contact 514 and wiper 510 and operates relay 509 through bank contact 515 and wiper 511, the ringing circuit is switched from wiper 513 to wiper 512 at one end and is switched at the other end from conductor 141 to conductor 144. The result is that the next application of ringing current is made from the 66-cycle generator through bank contact 516 and wiper 512 to conductor 144. This ringing current passes back over the established connection to the lower talking conductor 102 of the calling line, operating the 66-cycle ringer at the calling substation A. This operation continues, the calling and called ringers being operated alternately, until the calling subscriber removes his receiver again or until the called subscriber responds. Assuming now that the calling subscriber responds to the ringing of his bell by removing his receiver, a direct-current bridge is placed

across the conductors of the line, whereupon the ring-cut-off-control relay 508 in the ring-back switch operates from battery through either wiper 512 or wiper 513, depending upon the position of relay 509, to ground over conductors 141 and 144 in series to either the lower resting contact or the upper working contact of relay 502, depending upon the position of this relay at this time. Upon operating, relay 508 closes a circuit for relay 507 through the associated contacts, whereupon relay 507 operates and locks itself; opens the ringing circuit at its lower armature; and at its middle armature it opens the circuit of the hang-up relay 501 and closes a circuit through the associated off-normal contacts for the release magnet 520. Release magnet 520 operates and restores the switch to its normal position in the usual manner. The circuit of the release magnet is opened when the normal position is reached.

After a slight interval, the slow-relay 501 falls back and shifts the conductors 141 and 144 back to line relay 503 again, whereupon line relay 503 reoperates and closes a circuit for the release relay 504 so as to maintain the release relay operated.

As a result of the restoration to normal of the ring-back switch, relay 502 operates again through the associated off-normal contacts from conductor 142, and the hang-up tone is disconnected from the line at off-normal contacts 521.

The two subscribers on the same line may now converse with each other in the usual manner.

When both subscribers replace their receivers at the end of the conversation, line relay 503 falls back and opens the circuit of the release relay. A moment later the release relay falls back and unlocks relays 505 and 507 at its upper armature, at the same time removing ground from release-trunk conductor 142 at its inner upper armature, whereupon relay 502 falls back. At the same time, the local selector and the lineswitch shown in Fig. 1 both are released responsive to the removal of the ground potential from conductor 142.

Semi-automatic to manual call

It will now be assumed that the subscriber at substation A desires to converse with a subscriber whose line terminates in the manual office shown in Fig. 3, or in some nearby office. It will be assumed, as before, that the local selector shown in Fig. 1 is seized when the lineswitch LS operates in response to the removal of the receiver at substation A and that the trunk line incoming to the trunk circuit TC1, Fig. 3, is seized by the secondary switch SS, Fig. 4. The operator is signalled in the hereinbefore described manner by the operation of line relay 301, Fig. 3, over conductor 315. When the operator responds, the hereinbefore described bridge is placed across

the tip and ring conductors of the jack J2 through the lower winding of relay 308 to extinguish the supervisory lamp in the cord circuit.

After inquiring as to the destination of the call, the operator completes the connection through the other end of the cord circuit used.

After the conversation has terminated, the two subscribers replace their receivers. When the receiver is replaced at the calling substation, line relay 121 of the local selector, Fig. 1, falls back and removes ground at its upper armature from release-trunk conductor 115, at the same time causing, at its lower contacts, the release of the inter-office trunk line by the secondary switch SS. When this occurs, the slow-acting relay 406 of the incoming selector, Fig. 4, falls back and reconnects conductors 314 and 315 to line relay 407 of the incoming selector. When this occurs, there is a reversal in the current flow through the polarized relay 306, Fig. 3, whereupon the polarized relay operates and at its upper armature opens the bridge across the tip and ring conductors of the jack J2, thereby giving the operator a disconnect signal. Upon perceiving this disconnect signal, the operator pulls down the connection, restoring conditions in the trunk circuit TC1 to normal.

Handling toll connections

Regarding the handling of toll connections that are completed to distant points, it may be pointed out that the toll connections in the semi-automatic exchange are handled through the toll board shown in Fig. 3. A toll connection originated by a subscriber in the semi-automatic exchange, for example, the subscriber at substation A, Fig. 1, is recorded by the operator at the local board, Fig. 3, which operator passes a ticket describing the desired connection to the operator at the toll board. After making the necessary ticket regarding the connection, the local operator requests the calling subscriber in the semi-automatic exchange to replace his receiver, and the connection to the operating center is released as soon as he does so. The operator pulls down the connection when she gets the disconnect signal.

When the operator at the toll board is ready to complete the connection, she inserts the plug of a cord circuit into the jack J1, whereupon sleeve relay 302 operates through the sleeve of the jack and the sleeve of the plug in series and disconnects line relay 301, at the same time bridging the polarized relay 306 across the trunk conductors. Relay 302 also grounds conductor 321 so as to light the busy lamp. Since the line relay 407 of the incoming selector, Fig. 4, is connected to the conductors 314 and 315 in the normal direction, as contrasted with the reversed connections between these conductors and an impulse relay such as relay 122, Fig. 1, the

5 polarized relay 306 operates when it is bridged across the conductors 314 and 315 by relay 302, and it opens the bridge across the tip and ring conductors of the jack J2, thereby giving the operator unanswered supervision. The discriminating relay 303 is not operated in this case.

10 When the toll operator inserts the plug of her dial cord (corresponding to the plug P of the dial cord DC) into the dial jack DJ1, the upper spring contacts of the dial jack close a circuit for relays 305, 309, and 310, whereupon these relays operate. A locking circuit for the upper winding of relay 305 is 15 closed from conductor 321. When relay 310 operates, it places a bridge across conductors 314 and 315 including contacts of relay 313, whereupon line relay 407 of the incoming selector, Fig. 4, operates over conductors 314 and 315 and prepares the selector for operation by operating release relay 408.

20 Now, when the toll operator dials the first digit in the number of the subscriber at substation A, the digit 2, for example, line relay 407 falls back twice momentarily, each time 25 closing a circuit through contacts of release relay 408 and series relay 409 for the vertical magnet 412. By the operation of the vertical magnet the wipers 415 and 417 of the selectors 30 are raised opposite the second level of bank contacts. The series relay 409 operates in the manner described in connection with the series relay 124 of the local selector and initiates the trunk-hunting operation of the 35 selector at the end of the vertical movement, this trunk hunting operation being effected by the action of rotary magnet 413 in connection with stepping relay 410.

40 When an idle trunk line is reached, switching relay 411 energizes in series with stepping relay 410 and disconnects ground from the operating and release circuit at its inner lower armature; shifts wiper 416 from the test circuit to the holding circuit at its inner upper armature; and at its upper and lower armatures it disconnects conductors 314 and 315 from the line relay 407 and extends them by 45 way of wipers 415 and 417 to the talking conductors of the seized trunk line, for example, conductors 145 and 148 of the trunk line extending to the connector shown in Fig. 2. The line relay 203 and the release relay 204 of the connector, Fig. 2, now operate and the latter places ground on conductor 50 146 so as to furnish a holding circuit for relay 411 of the incoming selector before release relay 408 of such selector has had time to fall back.

55 When the operator dials the next digit in the number, the line relay 203 of the connector, Fig. 2, responds and brings about the operation of vertical magnet 215 in the hereinbefore described manner.

60 When the next digit is dialled, rotary magnet 216 responds as described hereinbefore

and brings the wipers 211—214 into engagement with the terminals of the line of substation A, Fig. 1. Assuming that the line is idle, switching relay 209 operates through the cut-off relay 107 of the lineswitch LS 70 and transfers the impulse circuit from the rotary magnet 216 to the operating magnet of the party selector.

Having established the connection to the line, the toll operator now removes the plug 75 of the dial cord from the jack DJ1, leaving the connection in this condition until she has completed the connection to the desired distant line.

80 When the plug is removed from the dial jack DJ1, relays 305, 309, and 310 fall back, whereupon the connection is transferred from the tip and ring conductors of the dial jack through the normally closed contacts controlled by the upper and lower armatures 85 of relay 310 to the temporary bridge including resistance 312 and the contacts of the slow acting relay 309. A moment later relay 309 falls back and leaves the connection held up through the bridge including the upper 90 armature, operated, of relay 302, polarized relay 306, and the lower contacts of relays 305. Relay 306 operates in this bridge and opens the bridge across the tip and ring conductors of the jack J1, discriminating 95 relay 303 being non-operated in this case, whereupon the calling supervisory lamp in the operator's cord becomes lighted.

100 It will now be assumed that a subscriber on the line of substation A removes his receiver, possibly to make a call, while the connection is in this condition. When this occurs, the auxiliary back-bridge relay 302 operates through wipers 211 and 214, upper 105 and lower armatures, normal, of ring-cut-off relay 206, and the upper and lower armatures, normal, of relay 207. Relay 202 closes a local holding circuit for line relay 203 and disconnects the said line relay 203 from conductors 145 and 148. When this is done, relay 203 remains operated in the local circuit, but the polarized relay 306, Fig. 3, falls back and recloses the bridge across the tip and ring conductors of the cord circuit, giving the operator answered supervision. The operator responds by throwing her listening key and conversing with the subscriber on the line, telling him to withdraw temporarily until the toll connection has been completed.

110 When the subscriber on the line of substation A replaces his receiver, the auxiliary back-bridge relay 202 falls back and reestablishes the circuit of line relay 203 over conductors 145 and 148 in series with the polarized relay 306, Fig. 3. Relay 203, which relay may 115 fall back momentarily if it is placed in series with the polarized relay 306, Fig. 3, when it has previously been energized through a resistance such as the resistance of the trunk line from the manual office to the semi-auto- 120

matic exchange, does not fall back momentarily at this time because it has been energized in a local circuit of practically no external resistance. It may be pointed out that this is the reason why the contacts of the auxiliary back-bridge relay 202 are arranged to discontinue the flow of current over the conductors 145 and 148 in order to give supervision rather than reversing the current flow through the conductors to give supervision, as the line relay would momentarily fall back and advance the party selector if the connection to the conductors were merely reversed.

Assuming now that the operator has completed the connection to the distant called subscriber and is ready to call the subscriber at substation A, the operator re-inserts the plug of her dial cord into the dial jack DJ1, whereupon relays 309 and 310 again operate, preparing the circuit for dialing.

When the operator dials the stations digit 6, six impulses of current are transmitted over the circuit previously traced to the operating magnet of the party selector, Fig. 2, whereupon the wipers 221 and 222 are brought into engagement with the sixth set of associated bank contacts. The relay 207 is operated in the hereinbefore described manner at the end of the operation of the party selector, and it completes the ringing circuit, whereupon the current from the 66 cycle source is sent out through wipers 222 and 214 to the lower conductor 102 of the line of substation A so as to signal the subscriber thereat. It will be remembered that relay 207 opens the impulse circuit at its inner lower armature so that no further operation of the operating magnet of the party selector will take place until the connection has been released.

When the subscriber at substation A removes his receiver, ring-cut-off relay 206 of the connector, Fig. 2, operates and completes the talking circuit, whereupon back-bridge relay 201 operates and reverses the connection between line relay 203 and conductors 145 and 148. Line relay 203 momentarily falls back when this reversal takes place, but no particular effect is produced owing to the fact that the impulse circuit is open.

In the trunk circuit TC1, polarized relay 306 restores when the current flow through its winding is reversed, again completing the bridge through the lower winding of relay 308 across the tip and ring conductors of the jack J1. This gives the operator answered supervision.

The conversation now takes place in the usual manner.

When the conversation is over, the subscribers replace their receivers. When the receiver is replaced at substation A, back-bridge relay 201 of the connector falls back and reverses the current flow in the conductors 145 and 148 to normal, whereupon the

polarized relay 307, Fig. 3, reoperates and opens the bridge across the tip and ring conductors of the jack J1, giving the operator disconnect supervision.

When the operator withdraws the plug from the jack J1, relay 302 falls back and opens the bridge across the conductors 314 and 315 through relay 306 and reconnects relay 301 to conductor 315.

Line relay 203 of the connector, Fig. 2, now falls back and brings about the release of the connector and the incoming selector in the usual manner.

Incoming non-toll connection

Assuming now that the operator at the local board receives a call from a subscriber local to the manual exchange in which her switchboard is located, which call is intended for a subscriber of the semi-automatic exchange, the subscriber at substation A, for example, the operator at the local board completes this connection through a trunk line such as the one comprising conductors 314 and 315.

Assuming that this trunk line is idle, as evidenced by the unlighted condition of the busy lamp associated with the jack J2, the operator inserts the calling plug of the cord circuit in use into the jack J2, whereupon sleeve relay 302 and discriminating relay 303 both operate and relay 306 operates to give unanswered supervision.

The operator now inserts the plug P of the dial cord DC into the jack DJ2 and proceeds to dial the digits in the number of the called station. When this plug is inserted, relays 305, 309, and 310 operate as before, and relay 304 operates through contacts of discriminating relay 303 and unlocks relay 308.

The operator now dials the digits in the number of the subscriber at substation A, whereupon the incoming selector, Fig. 4, a connector, and a party selector, the connector and party selector shown in Fig. 2, for example, are operated to complete the connection.

When the operator withdraws the plug P from the dial jack DJ2, relays 310, 309, and 304 fall back. Relay 310 reconnects conductors 314 and 315, whereupon the temporary holding bridge through resistance 312 becomes effective and a parallel bridge through relay 306 becomes effective. Before relays 309 and 304 fall back, relay 306 receives sufficient current in multiple with the resistance 312 to operate and transfer the tip conductor from the lower winding of relay 308 to a new bridge including impedance 307. This new bridge is completed when relay 304 falls back and it includes the upper contacts of relay 304, armature of relay 306, operated, upper contacts of relays 305 and 303, impedance 307, lower contacts of relay 308, and the inner-lower contacts of relay 310. When this bridge is closed, the

calling supervisory lamp in the local operator's cord circuit is extinguished, giving her dark-shelf supervision without the necessity of the pressing on the ringing key by the operator.

5 When the called subscriber responds, the current flow is reversed in the conductors 314 and 315 whereupon relay 306 restores, shifting the bridge across the tip and ring conductors from impedance 307 to the lower winding of relay 308. Relay 308 operates in this bridge and locks itself at its upper armature to conductor 321 through contacts of relays 303 and 304. At its lower armature, relay 308 opens a further point in the bridge including the impedance 307. The answered state of the supervision in the calling end of the cord is maintained now through the bridge including the lower winding of relay 308.

10 When the called subscriber at substation A replaces his receiver at the end of the conversation, the current flow in conductors 314 and 315 is reversed to normal, whereupon polarized relay 306 again operates and opens the bridge across the tip and ring conductors of the jack through the lower winding of relay 308, at the same time closing a point in the bridge including impedance 307. This 15 bridge is not effective at this time due to the fact that relay 308 is operated and remains locked up. The operator, therefore, is given disconnect supervision and she pulls down the connection with the hereinbefore described results.

Out-of-order equipment

20 In order to explain the functioning of the out-of-order equipment, let it be assumed that the line of substation A, Fig. 1, becomes defective so that the lineswitch LS is operated when no one is calling on the line. In this case, a local selector, the one shown in the drawings, for example, is seized and the operator is signalled in the hereinbefore described manner.

25 When the operator responds to the call and attempts to converse, she, of course, gets no answer and she knows that the line is still in a calling condition from the state of supervision in her cord circuit as controlled by the reversed current flow from the impulse relay 122 of the local selector.

In order to dispose of the connection and free the interoffice trunk line, the operator 30 connects her calling device with the trunk line and dials the digit 3, the third level of the local selector being set aside for maintaining out-of-order connections.

35 When the digit 3 is dialled, the local selector in use raises its wipers opposite its third level of bank contacts and rotates them in search of an idle out-of-order trunk circuit. Upon finding such circuit, for example, the trunk circuit TC2, shown in the drawing, the 40 trunk line comprising conductors 149—152

leading to such trunk circuit is seized and the line relay thereof operates to place ground on the release trunk conductor 150 so as to maintain the local selector and lineswitch LS in an operated position. The line relay of the trunk circuit also places ground on the out-of-order conductor 151, extending a ground potential back through wiper 129, conductor 116, wiper 112 of the lineswitch LS, and contacts of the switching relay 107 to the out-of-order normal conductor 105.

45 Having dialled the out-of-order digit 3, the operator withdraws from the connection, whereupon the interoffice trunk line is released in the usual manner.

Assuming now that a calling subscriber uses the connector shown in Fig. 2 to extend a connection to the line of substation A, the line tests busy because of the ground potential on private normal conductor 104, and the busy relay 207 is accordingly operated when connection is made to the line. However, the busy tone is not transmitted back to the calling line owing to the fact that the out-of-order relay 210 is energized over the corresponding wiper 213 and the out-of-order normal conductor 105 to shift the tone circuit from the busy tone lead release to the out-of-order-tone lead.

50 Upon hearing this distinctive tone indicative of an out-of-order condition, the calling subscriber replaces his receiver, whereupon the attempted connection is released in the usual manner.

55 When the out-of-order condition of the line of substation A is remedied, the line relay of the trunk circuit TC2 falls back, permitting the lineswitch LS and the local selector to release.

60 What is claimed is:

1. In a telephone system, a semi-automatic exchange, a manual exchange, two-way trunk lines connecting said exchanges, equipment at said manual exchange for sending digits over said trunk lines to control the setting up of connections by the switching mechanism in said semi-automatic exchange, a group of local selectors responsive to the first digit of numbers in calls between two lines in the semi-automatic exchange, and a separate group of incoming selectors responsive to the first digit in calls incoming from the manual exchange to the semi-automatic exchange.

- erating either selector which is connected to said trunk line.
3. In a telephone system containing a semi-automatic exchange and a manual exchange from which the automatic switches in the semi-automatic exchange are controlled, local selectors in said semi-automatic exchange, each selector having an impulse relay, means responsive to a call on a semi-automatic line for seizing one of said local selectors and for automatically extending a connection from said local selector to said manual exchange, said means including a line relay in said local selector controlled over the calling semi-automatic line, operator-controlled means including said impulse relay for controlling said local selector and other switching mechanism to complete the connection to a semi-automatic line, and means controlled by the impulse relay for maintaining the line relay operated in a local circuit after the selector has been set.
4. In a telephone system, an operator's switchboard, a trunk line comprising two inductively coupled sections, automatic switching mechanism controlled from said switchboard to set up a connection over both sections of said trunk line to a party line, party-selecting means subsequently operated from said switchboard to select and bring about the signalling of the desired station on the party line, a supervisory relay operated over the second section of said trunk line to give supervision to the operator over the second sections in case a subscriber on the called line responds before said party-selecting means is operated, and a second supervisory relay operated instead of the first to give supervision when a subscriber on the called line responds after said party selecting mechanism has been operated.
5. In a party-line telephone system, an operator's switchboard, a trunk line, automatic switching mechanism controlled over said trunk line to set up a connection to a called party line, party-selecting means operated subsequently over said trunk line to select and bring about the signalling of the desired station on the party line, and means controllable from the called line before said party selecting means has been operated to place a given distinctive supervisory condition on the first section of said trunk line and controllable from the called line after said party selecting means has been operated to place a different distinctive supervisory condition on the said first section.
6. In a telephone system including a manual office and a semi-automatic office, trunk lines connecting said offices, means for setting up a connection from a calling semi-automatic line to said manual office over one of said trunk lines, means for thereupon closing a direct current signalling circuit over said trunk line to signal the operator in said man-

ual exchange, automatic switches in said semi-automatic office, operator controlled means for opening the signal circuit and for closing a loop supervisory circuit including the two conductors of said trunk line in series, an impulse relay included in said supervisory circuit at the semi-automatic exchange non-responsive to the flow of current over said circuit, and operator-controlled means for closing a setting circuit over the two conductors of said trunk line in series, said impulse relay being responsive to the closure of the latter circuit.

7. In a telephone system, a manual office and a semi-automatic office, trunk lines interconnecting said offices, means for setting up a connection from a semi-automatic line to said manual office over one of said trunk lines and for establishing a talking circuit and a supervisory circuit over said connection, a high-resistance supervisory device included in said connection at the manual office, an impulse relay included in said supervisory circuit at the semi-automatic office, said relay remaining non-operated due to the high resistance of said device, and operator-controlled means for establishing an impulse circuit over said connection exclusive of said high resistance supervisory device to operate said impulse relay, and automatic switching mechanism in the semi-automatic office, operative under control of said impulse relay to extend a connection from the calling line to a called line.

8. In a telephone system including a semi-automatic office and a manual office, trunk lines connecting said offices, means for setting up a talking connection from a calling line in said semi-automatic office to said manual office including one of said trunk lines, a supervisory circuit including said trunk line, a high resistance supervisory device in said circuit in the manual office, an impulse relay in said circuit in the semi-automatic office, means whereby the operator in the manual office can set up a dialling circuit over said connection by bypassing said high resistance supervisory device whereby said impulse relay is operated, and means responsive to the said operation of said impulse relay for nullifying said talking circuit.

9. In a telephone system, a semi-automatic exchange, a manual exchange, automatic switches in said semi-automatic exchange operable from said manual exchange to complete local connections and to complete connections incoming to said semi-automatic exchange from said manual exchange, each of said automatic switches having two talking conductors and an impulse conductor incoming thereto, means for seizing one of said switches in the course of setting up a local connection and for seizing it in the course of setting up an incoming connection,

6 said means including in each case circuit arrangements for closing a switch control circuit over said talking conductors, and circuit arrangements for operating said switch in one case by interrupting said control circuit and for operating said switch in the other case by sending impulses over said impulse conductor.

10. In a telephone system, an automatic switch, said switch having incoming there-
10 to two talking conductors and an impulse conductor, means for seizing said switch and for closing a switch control circuit over said talking conductors, and means for operating
15 said switch to extend the connection responsive either to interruptions in said control circuit or to the transmission of impulses over said impulse conductor while said control circuit remains closed.

20. 11. In a semi-automatic telephone system, a party line, a ring back circuit for signalling two sub-stations on said party line alternately, switching mechanism controlled over a connection from an operator's switch-
25 board for extending a connection from a calling line to said ring-back apparatus, and means for delaying the ring back operation until the calling party has replaced his receiver and until the connection to the
30 operator's switchboard has been broken.

12. In a telephone system, subscribers' lines, talking conductors, a busy-test conductor, and an out-of-order conductor associated with each line, means for extending
35 a connection to a line, means controlled over the busy-test conductor to inform the calling subscriber of the busy condition in case the line is busy, and means controlled over the out-of-order conductor for informing the
40 calling subscriber of the condition of the line in case it is out of order.

13. In a telephone system, subscribers' lines, automatic switches for extending connections from said lines, a group of out-of-
45 order circuits, and means inoperative in case one of said switches is seized responsive to an out-of-order condition on a subscriber's line for operating said switch to extend the connection to one of said out-of-order
50 circuits, and means responsive to such extension for placing an out-of-order test condition on the line.

14. In a telephone system, an inter-ex-
55 change trunk line, means for completing a connection to said trunk line in either exchange, means in the first exchange for sending impulses over said trunk line to the second exchange, two impulse receiving devices in the second exchange, means for causing one of said receiving devices to receive said impulses in case the trunk line was initially connected within the second exchange and for causing the other receiv-
60 ing device to receive said impulses in case

the trunk line was initially connected with in the first exchange.

15. In a telephone system, subscribers' lines, automatic switching mechanism for extending connections to said lines, means for signalling the calling subscriber and for denying the connection in case a called line is busy, and means for denying the connection and for signalling the calling subscriber in a distinctly different manner in case the called line is out of order.

16. In a telephone system, an automatic switching device having access to subscribers' lines to complete connections thereto from calling lines, said switching device including a busy relay arranged to prevent connection to a busy line and to bring about the application of a busy tone to the calling line when the called line is busy, said device containing also an out-of-order relay ar-
85 ranged to operate when the line is out of order to substitute an out-of-order tone for the busy tone, while the busy relay operates as before to deny the connection and prepare the tone circuit.

17. In a telephone system, a connector switch having access to called lines, said connector having a pair of talking wipers, a busy test wiper, and an out-of-order test wiper, means controlled over said busy test wiper for placing a busy tone on one of the incoming talking conductors of the connector when the called line is busy, and means controlled over the out-of-order test wiper for placing an out-of-order tone on one of the incoming talking conductors when the called line is out of order.

18. In a telephone system, a plurality of lines, a plurality of selectors, regular trunks accessible to the said selectors, special trunks accessible to the said selectors, means responsive to a call on one of said lines for effecting a connection between the calling line and an idle selector, whereby the selector may be operated to set up a connection to one of the regular trunks, said call-responsive means being also responsive to an out-of-order condition on a calling line for effecting a connection between the out-of-order line and the selector, means effective in the latter case for operating said selector to extend a connection to one of said special trunks, the connection between the line and the special trunk comprising a plurality of conductors, and means in the special trunk for placing a special out-of-order condition on the out-of-order line by placing a distinctive potential on one of said conductors.

19. In a telephone system, a line having two test conductors, switching apparatus for extending two classes of connections from said line, means effective in case the connection extended is of one class for placing a distinctive potential on only one of said two test conductors, and means effective in case

the extended connection is of the other class for placing a distinctive potential on the other of said conductors.

20. In a telephone system, a line having two test conductors, switching apparatus for extending two classes of connections from said line, means effective in case the connection extended is of one class for placing a distinctive potential on only one of said two test conductors, and means effective in case the extended connection is of the other class for placing a distinctive potential on each of said two conductors.

21. In a telephone system wherein connections are extended through an automatic switching device from a calling line to a called line, a relay associated with the automatic switching device and operable responsive to an out-of-order condition on the called line, and means including said relay for placing an indicative out-of-order tone on the calling line.

In witness whereof, I hereunto subscribe my name this 19th day of October, A. D. 1927.

25 LEONARD L. RUGGLES.
